OFFERING CONTAINER

Thomas V. Isaia, Chicago, Ill., assignor to Progressive Bronze Works, Inc., Chicago, Ill., a corporation of Illinois

Filed June 13, 1963, Ser. No. 75,333

Term of patent 14 years

(Cl. D34—11)

FIG. 2 is a side elevational view thereof.

FIG. 3 is a rear elevational view thereof.

FIG. 4 is a top plan view thereof.

FIG. 5 is a bottom plan view thereof.

FIG. 6 is a cross sectional view taken on the line 6—6.

The dominant features of my design are shown in full lines.

I claim:

The ornamental design for an offering container, as shown and described.
